O.P. D. 25,675

DESIGN.

C. T. ROBINSON.
CRADLE.

No. 25,675.

Patented June 23, 1896.

UNITED STATES PATENT OFFICE.

CHARLES T. ROBINSON, OF PINE BLUFF, ARKANSAS.

DESIGN FOR A CRADLE.

SPECIFICATION forming part of Design No. 25,675, dated June 23, 1896.

Application filed May 16, 1896. Serial No. 591,881. Term of patent 7 years.

To all whom it may concern:

Be it known that I, CHARLES T. ROBINSON, a citizen of the United States, residing at Pine Bluff, in the county of Jefferson and State of Arkansas, have invented a new and original Design for Cradles, of which the following is a specification.

This invention relates to a new and original design for cradles, and it has for its object to provide a design of this character that shall be both useful and ornamental.

The leading feature of the design resides in a frame having a rectangular box portion provided above the plane of its top with upright head and foot boards of different heights, the head-board being provided at its upper end with a horizontal rail supporting a scrolled crest-board and upwardly-projected ornamental knobs at its ends, a rectangular open panel immediately below said top rail of the head-board having a series of regularly-spaced vertical tapered ornamental columns, and a rectangular panel of latticework immediately below the panel of said ornamental columns, and said foot-board having a top rail supporting ornamental knobs at its ends, and an open rectangular panel immediately below said top rail, and having therein a series of regularly-spaced vertical tapered ornamental columns, and the cradle proper disposed above the box portion and between the head and foot boards of said frame, and having opposite rectangular side frames of vertically-disposed regularly-spaced tapered ornamental bars, and foot and end boards having arched top edges provided with oppositely-located scalloped portions.

In the drawings, Figure 1 is a perspective view of a cradle embodying the herein-described design. Fig. 2 is a vertical transverse sectional view thereof.

Referring to the accompanying drawings, the numeral 1 designates the cradle-frame,

having a rectangular box portion provided with a flat top 3, and above the said top at 45 its ends with upright head and foot boards 4 and 5, respectively. The boards 4 and 5 are of different heights, and the board 4 is provided at its upper end with a horizontal top rail 6, supporting on its ends the upwardly-projected ornamental knobs 7, between which knobs is located a scrolled crest-board 8. Immediately below the rail 6 the board 4 is provided with a rectangular open panel 9, having therein a series of regularly-spaced 55 vertical tapered ornamental columns 10, and immediately below the panel of the columns 10 the board 4 is further provided with a rectangular panel of latticework 11.

The foot-board 5 is provided with a top rail 60 12, supporting at its ends the upwardly-projected ornamental knobs 13, and immediately below the rail 12 the board 5 is provided with a rectangular open panel 14, having therein a series of regularly-spaced vertical tapered 65 ornamental columns 15.

The cradle proper, 16, is arranged above the flat top 3 and between the boards 4 and 5, and is provided with opposite rectangular side frames 17, of vertically-disposed and regularly-spaced tapered ornamental bars 18, and said cradle is further provided with the foot and end boards 19, having arched top edges 20, provided with oppositely-located scalloped portions 21.

Having thus described the invention, what I claim is—

The design for a cradle herein shown and described.

In testimony that I claim the foregoing as 80 my own I have hereto affixed my signature in the presence of two witnesses.

CHARLES T. ROBINSON.
